UNITED STATES PATENT OFFICE.

WILLIS L. GRAVELY AND EDWARD H. MILLER, OF DANVILLE, VIRGINIA.

DESIGN FOR PLUG-TOBACCO.

SPECIFICATION forming part of Design No. 12,273, dated May 24, 1881.

Application filed April 2, 1881. Term of patent 14 years.

To all whom it may concern:

Be it known that we, WILLIS L. GRAVELY and EDWARD H. MILLER, citizens of the United States, and residing at Danville, in the county of Pittsylvania and State of Virginia, have invented and produced a new Design for Plug-Tobacco, of which the following is a specification, reference being had to the accompanying drawings, forming part thereof, and in which—

10 Figure 1 is a plan view of our newly-designed tobacco-plug. Fig. 2 is a sectional view of the same on the line xx , Fig. 1; and Fig. 3 is a view in perspective of the plug ready pressed for the market.

15 Corresponding parts in the several figures are denoted by like letters of reference.

The leading feature of our design consists in the peculiar combination or arrangement of four rolls of tobacco, which are so combined as 20 to form a single plug.

The four separate rolls, which in the draw-

ings are indicated by the letters A A' A² A³, are bent so as to form links or bails, as clearly shown in Fig. 2 of the drawings. The ends of the first link, A, are inserted into the loop of 25 the second link or bail, A', the ends of which latter are inserted into the loop of the next adjoining bail, A². The ends of bail A² are inserted into the loop of bail A³, whose ends finally are inserted into the loop of bail A. 30

We claim—

The herein-described design for plug-tobacco, consisting of four inter-linked looped rolls, substantially as set forth.

In testimony that we claim the foregoing as 35 our own we have hereto affixed our signatures in presence of two witnesses.

WILLIS L. GRAVELY.
EDWARD H. MILLER.
